UNITED STATES PATENT OFFICE.

J. R. HOPKINS, OF AUBURN, NEW YORK.

IMPROVEMENT IN EVAPORATORS FOR SALTS.

Specification forming part of Letters Patent No. 15,975, dated October 28, 1856.

To all whom it may concern.

Be it known that I, JOHN R. HOPKINS, of Auburn, in the county of Cayuga and State of New York, have invented a new and Improved Apparatus for Evaporating Solutions, of which the following is a full and accurate description, reference being had to the accompanying drawings, and to the letters of reference marked thereon.

A, Figure 1, is a close boiler, of copper, iron, or other metal, connected with a vat or reservoir, D, of wood, metal, or other substance, by metallic pipes B and C, provided with gates or stop-cocks b and c. The vat D is divided by an inclined partition, F I G J, which extends on the same plane to the point K, and forms the bottom of the smaller and upper division.

The dotted lines J K and I C indicate the lower edges of triangular pieces fitted into opposite corners, by which the form of the bottom is made to converge toward a small aperture through the lowest part thereof at N. Between the apertures of the pipes B and C, which terminate in the division, is fitted an inclined shelf, O. (Shown by dotted lines between the triangular pieces L and M.) The lower and larger division is marked P. It extends under and beyond the upper division, and is open at Q. Below this division is a small compartment or chamber, R, connected therewith by the pipe S, having a cock, s, and a strainer or filter. (Shown by dots within and at the lowest point of division, P, about the aperture of the pipe S.)

T, Fig. 2, is a vat or reservoir, of wood, metal, or other substance, fitted to and designed, when in use, to sit immediately over the upper division of vat D, Fig. 1, and extends over the boiler A. It is elevated above in the drawings to show more distinctly the form of the upper division of vat D. The bottom of the vat T is constructed of a semicircular metallic plate, extending from end to end, with its concave side downward, and forming an arched space, which is divided by a vertical partition at G', all of which is shown by dotted lines. At the base of the larger division of this arched space, on each side, is an inclined conductor, V V, to carry off the water resulting from condensation of steam upon the semicircular metallic plate within this division. The steam remaining uncon-

dened is conducted to the atmosphere by the pipe F'.

C' and D' are two slides, in which is placed a glass window for the admission of light. The draft from the furnace is conducted into the other division of the arched space, which extends over the boiler, by the pipe A', where it is separated and thrown upon the semicircular metallic plate within this division by the angular plate, whose end is shown by the dotted lines which intersect at B', and then to the atmosphere by the pipe E', inserted through the top of this division.

The apparatus above described is designed for the evaporation of solutions whose solvent powers are increased by the application of heat and diminished by cooling.

In operating the part illustrated by Fig. 1, the gates or stop-cocks in the pipes are to be opened and the vat, boiler, and pipes charged with the solution, and kept charged above the aperture of the upper pipe so long as the operation is continued. The fire is then kindled, the solution contained in the boiler heated, and a current thereby produced, flowing through the boiler, pipes, and upper division of the vat. This current is regulated by the stop-cocks in the pipes. The solvent capacity of the solution forming this current is alternately increased by heat while passing through the boiler and diminished by cooling while passing through the upper division of the vat, where its volume is expanded over a large surface, and the steam generated in the boiler is allowed to escape into the atmosphere, and where, after it is concentrated to saturation, its salts are necessarily precipitated. These salts are gathered by the converging or hopper-shaped bottom of this division to its lowest point, where they pass through a small aperture into the relatively cool and quiescent strata of the solution contained in the lower division of the vat, and an equivalent portion of the solution passes upward through the aperture into the boiling current. These salts are to remain in the lower division of the vat until the crystals have attained the desired size, when they are to be withdrawn from the solution.

When solutions contain several salts differing in solubility and specific gravity—some greater and others less than the one desired—the salts of less solubility should be precipi-

tated from the solution in another vat before it is subjected to the operation above described. Salts of greater solubility and specific gravity impart the same qualities to their solutions, which, in a quiescent condition, range themselves in strata corresponding to the relative specific gravity of their salts, and may be approximately separated by allowing the heavier strata in succession to pass into the chamber underneath the lower division of the vat through a filter impervious to the passage of crystals already deposited, when, by closing the stop-cock in the pipe between the vat and chamber, the contents of the chamber may be removed and the chamber refilled as often as necessary without interruption to the evaporating operation in the upper division of the vat.

When evaporation is conducted on a scale to render the utmost economy of fuel necessary—as in the manufacture of common salt, alum, &c.—the vat described as Fig. 2 is to be placed over the boiler and the upper division of vat, Fig. 1. It is to be kept charged with the brine or other solution, and a less rapid evaporation maintained by the application of the waste heat from the furnace, and by condensation of the steam from the upper division of vat, Fig. 1, upon the arched metallic plate, which forms the bottom of vat, Fig. 2, thereby concentrating the solution preparatory to its more vigorous evaporation in the boiler and vat below.

The above description of my apparatus and its mode of operation, it is believed, will enable any person skilled in the art to which it relates to construct the same, or modify its operation to any solution within the range of its design and adaptation. Some of the effects peculiar to this apparatus, and which constitute its advantages over others heretofore in use, are: first, it enables the operator to

regulate the increase of temperature in the volume of the solution forcing the current through the boiler and upper division of the vat by means of the stop-cocks in the connecting-pipes, and prevents the separation of steam or the deposit of the salts from the solution until carried by the current away from the heated metallic surfaces of the boiler, thus obviating the formation of corrosive and non-conducting incrustations thereon; second, it permits a rapid ebullition in a relatively small portion of the solution at the surface of the vat, while the lower and much larger portion remains relatively cool and quiescent, thereby economizing so much fuel as would otherwise be necessary to maintain a temperature in the the whole body of the solution sufficient to produce an equal evaporation from the surface, and furnishing the most favorable conditions for the perfect crystallization of the salts depositing from the boiling current at the surface; third, it admits an approximate separation in solution of substances more soluble and heavier than the one desired in the manner already described, thus obviating the necessity of a periodical suspension of the evaporating process to discharge these substances which are continually accumulating in the mother solution.

What I claim as my invention, and desire to secure by Letters Patent, is—

The apparatus for the evaporation of solutions whose solvent capacities are increased by application of heat and diminished by cooling, consisting of a close boiler, in combination with one or more vats or reservoirs, arranged substantially in the manner described.

JOHN R. HOPKINS.
